DESIGN FOR A CARPET-PATTERN.

Specification forming part of Design No. 5,880, dated May 28, 1872.

Specification describing a Design for a Carpet-Pattern, produced or invented by ALFRED HEALD, of Philadelphia, Pennsylvania.

Design for a Carpet-Pattern.

The main features of my design, which is fully represented by the accompanying photograph, are the large medallions A, square or diamond-shaped figures B and B', and smaller square or diamond-shaped figures D, the corners of the latter being overlapped by both the medallions and figures B and B'. The medallion A has the peculiar scroll-like outline clearly represented in the drawing, and in the center of the same is an ornament, a, composed of dots of different sizes, arranged

in the form of a square. The figures B and B' vary slightly in the character of their borders, and said borders of both sets of figures are partially covered by foliated ornaments c and d.

Irrespective of the colors employed, I claim—

The design for a carpet-pattern substantially as described, and as illustrated in and by the accompanying drawing.

In testimony whereof I have signed my name to this specification in the presence of two subscribing witnesses.

ALFRED HEALD.
